UNITED STATES PATENT OFFICE

WAYNE F. PALMER, OF HOLYOKE, MASSACHUSETTS

TRACKWAY

Application filed July 8, 1930. Serial No. 466,472.

This invention relates to trackways, and has particular reference to trackways of adjustable length.

One object of the invention is to provide a trackway and a carriage therefor of sufficiently simple construction so that it may be adapted either to manual or to power propulsion. A further object is to provide a trackway which is adjustable in length so as to permit any desired length of travel of the carriage throughout a path having a generally straight central portion and curved ends.

The invention will now be described with reference to the accompanying drawings, in which:

Fig. 1 is a top plan view of the trackway and torch guiding carriage constructed in accordance with my invention;

Fig. 2 is a side elevation thereof;

Fig. 3 is a detail of a form of trackway adapted for power actuation of the carriage;

Fig. 4 is a transverse section showing the trackway and carriage in the position of Fig. 2;

Fig. 5 is a perspective view partly broken away, showing the manner of securing the adjustment of the length of track;

Fig. 6 is a sectional detail on line 6—6 of Fig. 2;

Fig. 7 is a top plan view of one modified form of carriage; and

Fig. 8 is a sectional elevation showing a further modified form of carriage adapted for coaction with the trackway shown in Fig. 3.

The device consists of a trackway adjustable in length to provide various lengths of path, and a carriage running in this trackway and carrying whatever device or instrument it is desired to convey. The trackway is composed of a pair of main channel members 15 having portions 16 extending at substantially right angles and joined to the main trackway portion by a smooth curve 17. The angular portion 16 of each track is secured to a base 18 serving the double purpose of holding the tracks in spaced relation and of anchoring them to the frame of the machine as will be described later. A second

base 19 holds a pair of channel tracks 20 generally similar to the angular portions 16 of the main track and having curved portions 21 joining them to the main channel members 15. Each of the channel tracks 20 is provided with a tongue 22 fitting within the main channel section, as best shown in Fig. 5, and being beveled off as at 23 so that a smooth incline is presented from the bottom of the main channel to the bottom of the channel in the curved portion 21. The channel tracks 20 can be secured in any desired position along the main channel by set screws or any similar devices. It will be seen that the composite channel thus formed is continuous, but that the channel sections 20 are somewhat closer together than the channel sections 15.

Running in these channel tracks is a carriage 25 having shafts 26, four in number as shown, extending toward the channels and being pressed outwardly by springs 27 mounted within recesses in the carriage. At the channel ends of these shafts may be mounted anti-friction rolls of the type shown at 28 in Fig. 1 or at 29 in Fig. 7. This carriage will of course traverse the main section 15 and the curved and angular portions 16 and 17 of the same track without difficulty. When the carriage reaches the channel tracks 20, however, the rolls ride up on the bevel portion 23 thereby compressing the springs 27. The effect then is the same as shortening the shafts 26 upon which the rolls are mounted so that the carriage is permitted to travel along the channel sections 20 which are spaced together more closely than are the main trackways. This will be true whatever the longitudinal adjustment of the channel sections 20 with respect to the main trackways, the device affording a simple way of varying the length of travel of the carriage in accordance with the size of work to be operated upon.

As thus far described, the carriage is carried along the trackway by manual effort. This is satisfactory in some cases but it is sometimes desirable to have the carriage propelled by power. A modification permitting this has been shown in Figs. 3 and 8. In this

case the rolls at the end of the shafts 27 are indicated at 50 and are preferably freely rotatable on the shafts. The shafts carry gears 51 in mesh with racks 52 cut into the channel members 15 or racks 53 in the channel members 20. The shafts 26 of at least one set are splined together as at 54 so that the gears will exert equal traction on both sides of the carriage. A separate gear 55 on one of the shafts 27 meshes with a wide gear 56 on a driven shaft 57. In using this type of construction, the channel sections 20 can be adjusted longitudinally of the tracks 15 only in multiples of the pitch of the racks 53 which are employed; but this is generally close enough for ordinary purposes. In this case, as in the one already described, the shafts in the carriage are moved toward each other, compressing the springs 27 as the carriage passes from the main track to the adjustable track section.

In order to relieve any end pressure which might otherwise be exerted on the gears 52, the rolls 50 are preferably made of larger diameter than the gears and strike on their sides against the edges 58 of the channel sections. The force causing compression of the springs 57 will thus be transmitted through the rollers and not through the gears. Power may be applied to the shaft 57 by a small motor mounted upon the carriage or by means of a flexible shaft from some external source.

What I claim is:

1. A device of the class described, comprising channeled tracks having opposed straight runs and angular portions, a pair of shiftable channeled tracks extending angularly from the straight run of the tracks and having tongues fitting into the channels in said straight runs, said shiftable tracks having the bottoms of their channels merging into the bottoms of the channels of the straight runs, and a carriage slideable in the channels and contractible transversely so as to pass from the straight runs to said shiftable tracks.

2. A device of the class described, comprising channeled tracks having opposed straight runs and angular portions, a pair of shiftable channeled tracks extending angularly from the straight run of the tracks and having tongues fitting into the channels in said straight runs, said shiftable tracks having the bottoms of their channels merging into the bottoms of the channels of the straight runs, a carriage slideable in the channels and contractible transversely so as to pass from the straight runs to said shiftable tracks, and means for propelling the carriage along the trackway.

3. A device of the class described, comprising channel tracks having opposed straight runs and angular portions, a pair of shiftable channeled tracks extending angularly from

the straight run of the tracks and having tongues fitting into the channels in said straight runs, said shiftable tracks having the bottoms of their channels merging into the bottoms of the channels of the straight runs, a carriage slideable in the channels and contractible transversely so as to pass from the straight runs to said shiftable tracks, racks mounted adjacent said tracks, and gears mounted on the carriage and rotatable in mesh with said racks to propel the carriage along the trackway.

4. A device of the class described comprising a pair of main opposed channeled tracks bent at one end to form angular portions joined by a curve with their straight portions, a pair of channeled tracks slideable along the straight portions of the main tracks and having angularly extending portions joined by a curve with said straight portions, said slideable tracks having tongue portions extending into the channels of the main tracks and beveled to form an inclined plane leading from the channels of the main tracks to the channels of the slideable tracks, said main and slideable tracks being provided with racks, a carriage having rotatable and yieldable rolls received in and guided by the channels of the main tracks, gears associated with at least some of the rolls and meshing with the racks on the trackway, said rolls and gears yielding towards each other as the carriage passes from the main track to the slideable track, and means for rotating the gears to cause travel of the carriage along the tracks.

In testimony whereof I have affixed my signature.

WAYNE F. PALMER.
